UNITED STATES PATENT OFFICE.

CHARLES J. WILEY, OF YORKTOWN, NEW YORK.

PRINTING-TELEGRAPH.

1,146,985.

Specification of Letters Patent. Patented July 20, 1915.

Application filed June 12, 1914. Serial No. 844,607.

To all whom it may concern:

Be it known that I, CHARLES J. WILEY, a citizen of the United States, residing at Yorktown, in the county of Westchester and State of New York, have invented an Improvement in Printing-Telegraphs, of which the following is a specification.

My present invention relates to a printing telegraph, and particularly to that class of printing telegraphs commonly known as stock tickers, and furthermore this invention is an improvement upon the printing telegraph instrument shown and described in my Patent No. 1,116,657, Nov. 10, 1914.

The printing telegraph shown and described in my aforesaid application comprises a plurality of printing telegraph instruments, with which a single tape is employed, together with means for maintaining the necessary slack in the tape between the printing instruments to enable the operator to use both instruments simultaneously or either instrument alone, the said devices being operated in such a manner that the slack in the tape between the instruments is controlled so that the feed of the tape does not in any manner interfere with the operation of the instrument.

As shown and described in the application aforesaid, this slack in the tape was produced by devices for maintaining a slack in the tape between the printing devices employed in a printing instrument.

Now, my present invention relates to an apparatus for accomplishing the same purpose, but instead of employing devices for causing the tape to sag between the printing instruments, I now employ devices for supporting the tape between the instruments and raising the same at predetermined intervals, under the control of the operator, so as to maintain the required slack in the tape to permit of the independent or simultaneous operation of the printing devices in the instrument, as will be hereinafter more particularly described.

In the drawing, Figure 1 is a side elevation, more or less diagrammatic, illustrating a printing telegraph instrument embodying my present invention. Fig. 2 is also a diagrammatic elevation of the transmitters employed, together with devices associated therewith. Fig. 3 is a diagrammatic plan of the parts of the apparatus, as shown in Fig. 1. Fig. 4 is a plan of the rod and support roll for the tape, and Fig. 5 is a side eleva-

tion of the counter-weight employed on this shaft, as shown in Fig. 4.

In carrying out my invention, I employ a plurality of printing devices, combined in a single instrument, and as shown in Fig. 1, I have illustrated two such printing devices combined with a single instrument. These printing devices are indicated at A and B, respectively, and are suitably mounted in a frame comprising side members 10 and 11, connected by cross bars 12.

The side members 10 and 11 of the frame, preferably centrally thereof, are slotted, as indicated at 13, for a purpose which will hereinafter appear. The printing apparatus A preferably comprises type wheel magnets 14, and type wheel 15, associated with which, as is customary, is an inking roll 16. This instrument also includes an escapement lever 17, carrying an armature so as to be operated by the magnets 14, and is associated with a train of gears 18, operated through a weight 19 or any other suitable means, such as a spring.

20 indicates a printing magnet of the instrument A and 21 its armature, which is carried by a printing lever 22 and maintained normally in position against a stop 23 by a spring 24, or otherwise, and the printing lever 22 is provided with tape feed rolls 25. Similarly, the printing instrument B comprises type wheel magnets 26 and a type wheel 27, with which there is associated an ink roll 28, an escapement lever 29, carrying 20 a printing magnet 30 and an armature 31, or otherwise, and the printing lever 29 is provided with tape feed rolls 32. The instrument B also includes a printing 25 magnet 32, the armature 33 of which is fixed in a printing lever 34 normally maintained against a stop 35 by a spring 36 or otherwise, and the printing lever 34 carries suitable tape feed rolls 37.

Suitably connected in the sides of the frame is a shaft, upon which a reel 38 is mounted. The tape 39 is taken from the reel and fed through the rolls 37 of the instrument B, and also through the similar rolls 25 of the instrument A.

The parts of the apparatus, as hereinbefore described, are those common to printing instruments known as stock tickers.

As will also be seen by reference to Fig. 1, in a suitable position, the side member 10 of the frame is provided with an arbor 40, upon

which a ratchet 41 and a disk 42 are mounted. The bell crank lever 43 is also mounted on the arbor 40, and at the end of one of its arms is provided with a pawl 44, adapted to engage the teeth of the ratchet 41 and to be maintained in contact therewith by a spring 45, or otherwise. The free end of the other arm of the bell crank lever 43 is connected by a link 46 to a lever 47, which, at one end, 10 is pivotally connected to the side member 10 of the frame, as indicated at 48:

Secured in the opposite end of the lever 47 is the armature 49 of a magnet 50. The lever 47 is normally maintained in its initial 15 position, as shown in Fig. 1, by means of a spring 51 connected at one end to the lever and at the other in a pin provided for this purpose on the side member 10 of the frame. This, as will be understood, also maintains 20 the link 46 and the bell crank lever 47 in their initial positions, as indicated in this figure of the drawing. An arbor 53 is also secured in a suitable position on the side member 10 of the frame, and carries a bell 25 crank lever 54. In one arm of the bell crank lever 54 there is secured the armature 55 of a magnet 56. The bell crank lever 54 is normally maintained in its initial position against an adjustable stop 57 by means of a 30 spring 58 or otherwise. At the free end of the other arm of the bell crank lever 54, the same is connected to a lever 60 by means of a link 59. The lever 60 is pivotally mounted, as indicated at 61, to the side member 10 35 of the frame, and at its free end, is provided with a projection or hook, the purpose of which will be hereinafter explained. I also employ a lever 62, which, adjacent one end, is mounted on an arbor 63, also fixed in the 40 side member 10 of the frame. Pivotally connected to the left-hand end of the lever 62, as viewed in Fig. 1, is a cup shaped lift 64. The lever 62 is connected to the disk 42 by 45 means of a link 65, the upper end of the link being pivotally connected to the lever 62 and the lower end of the link pivotally connected in the disk 42.

It is to be understood that the ratchet 41 and the disk 42 are mounted to turn in unison freely on their arbor 40, and that the lever 62 is normally maintained in its initial position, as shown in Fig. 1, by means of a spring 66, and an adjusting screw, by means of which the tension exerted against the lever to maintain the same in a raised position may be adjusted.

Now by referring to Fig. 3, as well as to Fig. 1, it will be seen that I also employ a rod 68, fitted with a collar 69, extending 60 from opposite sides of which there are trunnions 70 journaled in bearings provided therefor in brackets 71, suitably secured in position on the side member 11 of the frame of the apparatus. This rod 68 is sufficiently 75 long to extend across the apparatus and to

extend an appreciable distance beyond the side member 10 thereof, exteriorly of which member the rod 66 is provided with a tape roll 72. The tape roll 72 is so placed on the rod as to come directly beneath that portion 70 of the tape which extends between the instruments A and B.

On the opposite end of the rods 68, I employ a counter-weight 73, which may be secured in position thereon by a set screw 74, 75 or otherwise. In practice, this counter-weight 73 is so placed on the rod 66 as to slightly more than overbalance the opposite or long end of the rod carrying the tape roll 72, so that the tendency is, at all times, to 80 slightly raise that portion of the tape extending between the printing instruments.

In conjunction with the parts of the apparatus hereinbefore described, and as will be seen by reference to Fig. 2, I also employ 85 transmitting instruments, indicated at C—D respectively. The transmitter C is provided with terminals 75—76, and the transmitter D with similar terminals 77—78, and each of these transmitters includes a contact ring 79, 90 an operating key 80, a toothed wheel 81, turned by the key 80, levers 82 and 83 pivoted at corresponding ends and adapted at their free ends to bear against the toothed wheel 81, and contacts 84—85, and 86—87, 95 by means of which, as will be understood, the current in the line leading to and from the transmitter is reversed, and a battery 88, the terminals of which are connected to the pivotal points of the levers 82 and 83. I 100 also employ an auxiliary magnet 89, having an armature 90 secured in the lever 91, which is normally maintained against a stop 93 by means of a spring 92 or otherwise. In conjunction with the auxiliary magnet 89 is a 105 switch comprising a lever 94, and contact terminals 95 and 96. I also employ an auxiliary magnet 97, the armature 98 of which is carried by a lever 99, and the lever 99 is normally maintained against a stop contact 110 101 by a spring 100, or otherwise. Also associated with the auxiliary magnet 97 is a switch comprising a lever 102, and contact terminals 103 and 104.

The magnets 14—20 of the printing instrument A, as well as the magnet 56, are connected, in series in the same line, indicated at 105, and also the magnets 26 and 32 of the printing instrument B, as well as the magnet 50, are also connected in series 110 in a common line, indicated at 106. One end of the line 106 is connected to the lever 94 of the switch associated with the auxiliary magnet 89, and the other end of the line 106 to one terminal of the auxiliary 115 magnet 97.

The connection 107 is made between the contact 93 and the terminal 77 of the transmitter D, and the lever 91 associated with the auxiliary magnet 89, is also connected 120 125 130

to the terminal 77 of the transmitter D by a line 108. Similarly one end of the line 105 is connected to the lever 102 forming part of the switch associated with the auxiliary magnet 97 and the opposite end of the line 105 is connected to one terminal of the auxiliary magnet 89. The terminal 75 of the transmitter C is connected to the contact 103 by a line 110, and this terminal 75 of the transmitter C is also connected to the lever 99 associated with the auxiliary magnet 97 by a lead wire 111. The opposite terminal of the auxiliary magnet 89 is connected to the terminal 76 of the transmitter C by a lead wire 109, and similarly the opposite terminal of the auxiliary magnet 97 is connected to the terminal 78 of the transmitter D by a lead wire 112. Connected across the line 105, I may also place a line 113, in which there is a battery 114 and a switch 115, the purpose of which will be hereinafter described.

Now by referring again to Fig. 1, it will also be seen that I may employ guard pins 116 and 117 for preventing the tape, when raised, from coming into contact with the type wheels, as will also be hereinafter described.

In the operation of the hereinbefore described apparatus, the printing instruments may be operated simultaneously, or either one separately, as hereinbefore stated. In the simultaneous operation of the instruments, the lever 94 is moved to bear against the contact 95, and similarly the lever 102 is moved to bear against the contact 103. The printing instrument A is operated through the transmitter C, and the line 105, while the printing instrument B is operated through the transmitter D and the line 106. The magnets 14 and 20 of the printing instrument A are wound so as to be energized by the passage of a current of a given strength, whereas it is necessary to pass a stronger current through the line 105 in order to energize the magnet 56. This also energizes the magnet 20 thereby operating and locking in position the printing devices of instrument A. On the other hand, the magnets 26, 32 and 50 of the printing instrument B, are all wound so as to be energized by the passage of a current of given strength.

In the operation of the printing instrument B, it will therefore be apparent that each time the magnet 32 is energized to operate the printing lever 34, the magnet 50 will also be energized to operate the lever 47. In operating the lever 47, the bell crank lever 43 will be actuated, and will impart a partial revolution to the ratchet 41, through the pawl 44, so that by the successive operations of the printing instrument B, a step-by-step movement will be given to the ratchet 41 and the disk 42, in

a clockwise direction, as viewed in Fig. 1, and this movement, through the link 65, will progressively draw down or depress the lever 62 and the cup shaped lift 64 carried thereby. This, as will be understood, frees the lift from the under surface of the tape roll 72, and permits the same to move freely, due to the action of the tape and the counter-weight 73, it being understood that the tape which extends between the printing instruments A—B passes over the upper surface of the roller 72, as plainly indicated in Figs. 1 and 3 of the drawing. The step-by-step movement imparted to the ratchet 41 and disk 42 is continued until the link 65 comes into contact with the projecting end of the lever 60, when, as will be understood, the parts are locked and the continued operation of the printing instrument B will not affect or cause any movement in these parts. Now, at predetermined intervals, or as may be necessary, depending upon the relative rapidity with which the printing instruments A—B are used, the operator may send an abnormally strong current through the line 105, in order to energize the magnet 56, and in so doing the armature 55 thereof is attracted against the action of the spring 58 and the upper arm of the bell crank lever 54 is moved from right to left, as viewed in Fig. 1, thereby, through the link 59, swinging the lever 60, also from right to left, as viewed in this figure, sufficiently far to permit the end of the lever 60 to entirely clear the link 65. Inasmuch as the latter, when in its locked position, is moved past the center, it will be readily understood that when so released the ratchet 41 and disk 42, being free to turn, the lever 62 will be raised instantly and with considerable force, depending upon the tension placed on the spring 66, and in its return movement the cup shaped lift 64 will strike the under side of the tape roll 72, quickly raising the same and carrying the tape with it, in order to establish or reestablish a proper or desired slack in the tape between the printing instruments.

The guard pins 116 and 117 are employed, as will be appreciated, to prevent the adjacent portions of the tape from coming into contact with the surface of the type wheels during this operation.

By reference to Fig. 2, it will be seen that the additional current, or current of abnormal strength, may be caused to pass through the line 105 by closing the switch 115 in the line 113, extending across the line 105, and in which the battery 114 or other source of energy is placed.

It will be further understood that in adjusting the tape, as hereinbefore described, it will be necessary either to have the printing devices of the instrument A in a locked

position or to have the type wheels of both instruments in unison.

By reference to Fig. 2, of course it will be apparent that in the operation of the apparatus, as hereinbefore described, the printing instrument A is operated from the transmitter C, and that the auxiliary magnet 89 is associated with the transmitter D and is in the line 105 leading to the printing instrument A, operated by the transmitter C, and that the auxiliary magnet 97, associated with the transmitter C, is in the line 106 extending from the transmitter D to the printing instrument B.

Now, assuming it is desired to operate the printing instrument A independently of the printing instrument B, it will be necessary to shift the lever 94 from its position bearing on the contact 95 to a position in which it will bear against the contact 96. With the levers in this position, the currents in the operation of the instrument A will pass from the terminal 75 of transmitter C through the line 110 to the contact 103 and the lever 102, thereby through the side of the line 105 to the magnets 56, 20 and 14, respectively, thence through the other side of the line 105 to the auxiliary magnet 89, and thence by the line 109 to the other terminal 76 of transmitter C. This current, it is noted, will pass through the auxiliary magnet 89, and in so doing energize the same, attracting its armature 90, and thereby swinging the lever 91 from its normal position against the stop 93 to a position in which the free end of the lever bears against the screw adjustable in the contact 96, thereby completing a circuit from the lever 90 through the line 108, through the transmitter D, through the line 112, the auxiliary magnet 97, one side of the line 106 to the printing instrument B, thence through the magnets 26, 32 and 50 of the printing instrument B, and thence through the other side of the line 106 to the lever 94, and the contact 96. Closing this circuit, as will be understood, energizes the printing magnet 32 and actuates the printing lever 34, which, in turn, operates the devices for feeding the tape through these instruments, so that each time the printing instrument A is operated the printing instrument B will also be operated and the tape fed through both instruments simultaneously, so that when once the desired slack in the tape between the instruments is effected, the same will be maintained so long as the instrument A is used independently of the instrument B.

It will be obvious that to operate the printing instrument B from the transmitter D independently of the printing instrument A, it will only be necessary to reverse the position of the levers 94 and 102, that is to say, in so doing, the lever 94 remains in its position bearing against the contact 95, whereas

the lever 102 is moved to a position in which it will bear against the contact 104.

I claim as my invention:

1. In a printing telegraph, a plurality of independently operated printing instruments, a single tape common to all the said instruments, and means for supporting the tape between the printing instruments and maintaining a predetermined slack in the tape lengthwise thereof between adjacent printing instruments. 70

2. In a printing telegraph, a plurality of printing instruments, a single tape common to all said instruments, a transmitter for each printing instrument, and means associated with the said printing instruments for supporting the tape between adjacent instruments and maintaining a predetermined slack in the said tape lengthwise thereof. 80

3. In a printing telegraph, a pair of independently operated printing instruments, a single tape common to both printing instruments, and means for supporting the tape between the instruments and maintaining a predetermined slack in said tape lengthwise thereof. 85

4. In a printing telegraph, a pair of printing instruments, a single tape common to both printing instruments, a transmitter for each printing instrument, and means for supporting the tape between the said printing instruments and maintaining a predetermined slack in the said tape lengthwise thereof. 95

5. In a printing telegraph, a frame, a front and a rear printing instrument mounted in the said frame, a tape common to both the said instruments, a magnet in the line leading to the front printing instrument, means for supporting the tape between the said instruments, and devices actuated by the said magnet to contact with the said means to raise the same and the tape to maintain a predetermined slack therein lengthwise of the tape between the said instruments. 100

6. In a printing telegraph, a frame, a front and rear printing instrument mounted in the frame, a tape common to both the said frames, a rod pivotally mounted on the said frame, a tape roll carried by the said rod and adapted to support the tape between the said instruments, and devices actuated at predetermined intervals for raising the said tape roll to maintain a predetermined slack in the tape lengthwise thereof between the said printing instruments. 115

7. In a printing telegraph, a frame, a front and rear printing instrument mounted in the said frame, a tape common to both the said instruments, a rod pivotally mounted in the said frame, a tape roll carried by the rod, means for causing the said rod and tape roll to yieldingly support the said tape between the said instruments, a lever mount- 120

130

ed in the said frame, a lift carried by the said lever, and means for raising the said lever and lift at predetermined intervals to maintain a predetermined slack in the tape lengthwise thereof between the said printing instruments.

8. In a printing telegraph, a frame, a front and rear printing instrument mounted in the said frame, a tape common to both the 10 said instruments, a rod pivotally mounted in the said frame, a tape roll carried by the rod, means for causing the said rod and tape roll to yieldingly support the said tape between the said instruments, a lever mounted 15 in the said frame, a lift carried by the said lever, means in the line to the said rear printing instrument and actuated by passing a current therethrough for progressively depressing the said lever and lift, means for 20 locking the said lever and lift after the same has reached a predetermined position, and devices in the line to the front printing instrument and actuated by the passage of a current therethrough for releasing the said 25 locking means, permitting the lever and lift to return to their initial positions and in so doing to raise the said tape roll and tape to maintain a predetermined slack in the tape lengthwise thereof between the printing 30 instruments.

9. In a printing telegraph, a frame, a front and rear printing instrument mounted in the said frame, a tape common to both the said instruments, a rod pivotally mounted in the said frame, a tape roll carried by the rod, a ratchet, a disk, an arbor upon which the said disk and ratchet are mounted, a link connecting the said lever and disk, a magnet in the line to the rear printing 35 instrument, means actuated by the magnet for imparting a step-by-step movement to the said ratchet and disk, thereby progressively depressing the said lever and lift, means for locking the said lever and lift after the 40 ratchet and disk have turned a predetermined portion of a revolution, and means in the circuit to the front printing instrument and actuated by the passage of a current therethrough for releasing the said means 45 for locking the lever and lift in position, whereby the same may return to their initial 50 positions and in so doing raise the tape roll and tape to maintain a predetermined slack in the tape lengthwise thereof between the printing 55 instruments.

10. In a printing telegraph, a frame, a front and rear printing instrument mounted in the said frame, a tape common to both the said instruments, a rod pivotally mounted in the said frame, a tape roll carried by the rod, a ratchet, a disk, an arbor upon 60

which the said disk and ratchet are mounted, a link connecting the said lever and disk, a magnet in the line to the rear printing instrument, means actuated by the magnet for 65 imparting a step-by-step movement to the said ratchet and disk, thereby progressively depressing the said lever and lift, a hook lever against which the said link contacts after the ratchet and disk have been turned 70 through a predetermined portion of a revolution, in order to lock these parts and the said lever and lift in position, and devices in the circuit to the printing instrument and actuated by passing a current therethrough 75 and for releasing the said hook lever, permitting the ratchet and disk to revolve and the lever and lift to be raised to their initial positions, thereby raising the tape roll and tape in order to maintain a predetermined 80 slack in the tape lengthwise thereof between the printing instruments.

11. In a printing telegraph, a frame, a front and rear printing instrument mounted in the said frame, a tape common to both the said instruments, a rod pivotally mounted in the said frame, a tape roll carried by the rod, a ratchet, a disk, an arbor upon which the said disk and ratchet are mounted, a link connecting the said lever and disk, a magnet in the line to the rear printing instrument, means actuated by the magnet for 85 imparting a step-by-step movement to the said ratchet and disk, thereby progressively depressing the said lever and lift, a hook lever against which the said link contacts after the ratchet and disk have been turned 90 through a predetermined portion of a revolution, in order to lock these parts and the said lever and lift in position, a magnet 95 in the circuit to the front printing instrument, an armature for the magnet, and connections between the said armature and the said hook lever for swinging the hook lever free of the said link to permit the ratchet 100 and disk, as well as the said lever and lift, to return to their normal positions, thereby raising the said tape roll and tape in order to maintain a predetermined slack in the 105 tape lengthwise thereof between the printing instruments.

12. In a printing telegraph, a pair of independently operative printing instruments, a tape common to both said instruments, and means for yieldingly supporting the tape between said instruments when either instrument is used independently of the other.

Signed by me this 8th day of June, 1914.
CHARLES J. WILEY.
